ALFRED F. BILES, OF PORTLAND, OREGON.

METHOD OF MANUFACTURE OF WOODEN PANEL DOORS.

Application filed May 19, 1924. Serial No. 714,402.

To all whom it may concern:

Be it known that I, ALFRED F. BILES, a citizen of the United States, and a resident of Portland, county of Multnomah, and 5 State of Oregon, have invented a new and useful Improvement in Methods of Manufacture of Wooden Panel Doors, of which the following is a specification.

My invention relates to wooden panel doors and particularly to that type in which the panel constitutes a substantial portion of the door.

As well known, wood is greatly affected by moisture and thus tends to expand or contract appreciably with changes in the weather. It is also well known that wood will expand or contract most across the grain, while its expansion and contraction with the grain is negligible.

Since in doors of this type the panel constitutes a substantial portion of the door, it is therefore more affected by the moisture than other portions of the door and tends to expand or contract disproportionately to such other portions. The frame portions of the door are furthermore free to expand outwardly and reduce only to a negligible degree the area which they enclose. But the panel is encompassed and bound by the frame portions and must thus displace said frame portions or if weaker, can only accommodate its own expansion by buckling which renders the door unsightly and may even cause the cracking of the panel.

The solution of the problem which might suggest itself is to fill the pores of the panel so as to exclude air and the moisture which it carries, but the problem still remains how best to insure an efficient filling of the pores.

I attain the object of my invention by dipping the panel—or if the latter be a composite structure, then its component units—into hot linseed oil before being inserted in the door. Such dipping tends to cause the air in the pores to expand and thus be partially expelled and when the door is then removed from the hot linseed bath, the contraction of the air in its pores and the ensuing partial vacuum so induced tends to suck in a sufficient quantity of the linseed oil to render the panels weather proof. Besides, my method of thus treating the door panels only may be carried out with negligible expense in the manufacture of the doors and the panel when so treated is in

condition for being finished by the application of paints or varnishes as may be desired.

In the accompanying drawings, I have 60 illustrated one type of panel door to which my invention is particularly directed and the details of my method are hereinafter fully described.

Referring now to said accompanying 65 drawings:

Fig. 1 shows an elevation of a door with parts broken away to show details of construction; and

Fig. 2 shows a sectional view taken along 70 the line 2—2 of Fig. 1.

The door is made up of a frame section *a* which constitutes the border of the door. This frame is made up of a top rail *a'*, stiles *a*² at the sides of the door, and a bottom rail *a*³. Encompassed by the frame are the panels *b* and *c* and the panes of glass *d* in the upper portion of the door. The panes of glass are separated from each other by sash members *e* and *e'* and the panel *b* is 80 separated therefrom by the lock rail *f* and from the panel *c* by an intermediate rail *g*. As illustrated, the panels *b* and *c* are built up of a number of abutting parallel members *b'* and *c'* which are preferably of tongue 85 and groove construction to make a solid and water tight door. The grain in each of these members *b'* runs lengthwise of the member and thus the entire composite member is made up of members in which the 90 grain runs substantially in the same direction and thus the panel when affected by moisture will elongate in one direction and substantially none in the other direction. In other words, when the composite panel *b* 95 becomes moist, the expansion of the panel as a whole will be the summation of the expansions of each of its individual boards, which is also the case of the boards *c'* in the panel *c*. If the panels are permitted to expand, they will either tend to force the longitudinal stiles *a*² away from their connections with the rails or else will tend to buckle the panels so that they will not remain flat.

My method of dipping each individual 100 board *b'*, or each panel, in case the panel is made up of a single panel, effectively fills the exterior cells of the wood in each member and seals the same so that moisture cannot enter and thus expand the member.

I am aware that it is old to provide panels 110 which are made up of veneering or made up

of strips of material in which the grain in each member is cross wise to the adjacent strips and I am also aware that it is old to apply a coating of linseed oil or paint to the panels to seal the same in order to prevent the panels from swelling. Applying said oil or paint with a brush is ineffective; first, because the oil does not fill the cells of the wood and only partially covers the surface, and second, because when the oil is applied in this manner, it cools very rapidly and thus cannot be applied onto the wood at the necessary high degree of temperature, to cause saturation. When the panel is immersed in a vat of hot linseed oil, however, the linseed oil is applied to the exterior portion of each panel, and being held at a constant high temperature enters and fills the surface pores as a heated liquid and completely seals the same, and when the member subsequently cools, causes the oil to be drawn into the wood to relieve the resultant partial vacuum.

I claim:

25 1. In the manufacture of wooden panel

doors of the character described, the method of rendering the door unaffected by moisture consisting in dipping the panel of the door only in a hot material impervious to moisture, and uniting the same to an untreated frame work.

2. In the manufacture of wooden panel doors of the character described, the method of rendering the door unaffected by moisture consisting in dipping the panel of the door only in hot linseed oil, and uniting the same to an untreated frame work.

3. A wooden panel door comprising an untreated frame and a panel united thereto, said panel prior to the assembly of the door having been treated with a hot material impervious to moisture to render the entire door unaffected by moisture.

4. A wooden panel door comprising an untreated frame and a panel united thereto, said panel prior to the assembly of the door having been treated with hot linseed oil to render the entire door unaffected by moisture.

ALFRED F. BILES.
